(57) **CLAIM**

The ornamental design for an automobile chassis kit, as shown and described.

DESCRIPTION

FIG. 1 is a perspective view of the exterior surfaces of the front and right side of an automobile chassis kit, the left side of the chassis kit being identical to the right side of the chassis kit, the interior surfaces having no ornamentality; FIG. 2 is a perspective view of the exterior surfaces of the rear and left sides of the chassis kit illustrated in FIG. 1, the right side of the chassis kit being identical to the left side of the chassis kit, the interior surfaces having no ornamentality; FIG. 3 is a side view showing the exterior surfaces of the right side of the chassis kit illustrated in FIG. 1, the left side of the chassis kit being identical to the right side of the chassis kit, the interior surfaces having no ornamentality; FIG. 4 is a front view of the exterior surfaces of the chassis kit illustrated in FIG. 1, the interior surfaces having no ornamentality;

FIG. 5 is a rear view of the exterior surfaces of the chassis kit illustrated in FIG. 1, the interior surfaces having no ornamentality; and,

FIG. 6 is a top plan view of the exterior surfaces of the chassis kit illustrated in FIG. 1, the interior surfaces having no ornamentality.

The portions of the automobile shown in broken lines are for illustrative purposes only and form no part of the claimed design.
